ROTATION AND FEED CONTROLLING
VALVE FOR ROCK DRILLS

Theodore A. Schmidt, Berea, Ohio, assignor to
Le Roi Company, Milwaukee, Wis., a corpora-
tion of Wisconsin

Application September 10, 1949, Serial No. 115,043

2 Claims. (Cl. 121—5)

1

This invention relates broadly to fluid actuated rock drills of the stoper type, but more particularly to an improved valve structure for controlling the feed and rotation mechanisms of such drills.

One object of this invention is to provide a self-rotating stoper with improved controls which will facilitate and render safer the operation of the tool.

Another object of this invention is to provide a self-rotating stoper with improved valves for controlling the feed and rotation mechanisms of the tool, the valves being arranged and disposed in a manner rendering them readily operable by the operator while normally holding the stoper to the work.

Other objects more or less ancillary to the foregoing and the manner in which all the various objects are realized will appear in the following description which, considered in connection with the accompanying drawings, sets forth the preferred embodiment of the invention.

In the drawings:

Figure 1 is a longitudinal sectional view of a stoper drill embodying the invention.

Figure 2 is an enlarged cross sectional view taken on line 2—2 in Figure 1.

Figure 3 is a cross sectional view taken on line 3—3 in Figure 1.

Figure 4 is a cross sectional view taken on line 4—4 in Figure 2.

The tool embodying the invention is a fluid actuated rock drill of the stoper type which comprises a drilling motor, a feed mechanism and an auxiliary handle generally designated by A, B and C respectively.

The drilling motor is of the reciprocating piston type well known in this art, and can briefly be described to include a cylinder 10 having a piston 11 reciprocable therein. The piston 11 includes a stem 12 capable of delivering impacts on the shank 13 of a cutting tool or drill steel 14, which shank is slidably mounted within a chuck 15. This chuck is rotatably mounted within the front or upper end of a chuck housing 16, which also accommodates a chuck bushing 17 geared to the chuck 15 for transmitting rotation thereto. Internally, the chuck bushing 17 is formed with splines which mesh with similar splines formed on the piston stem 12.

Within the rear or lower end of the cylinder 10 is mounted an automatic valve mechanism, including, among other things, a valve 18 which is automatically movable between valve seats for controlling the admission of motive fluid alter-

nately to the ends of the cylinder 10 for effecting the reciprocation of the piston 11. Motive fluid is admitted to the valve 18 from a throttle valve 20 through ports and passages, not shown. The throttle valve 20 is rotatably mounted within a back head 21, and is provided with a central port 22 having motive fluid supplied thereto in a manner well known in tools of this type.

Extending through the valve 18, there is a stem 23 formed with rifle splines slidably interlocked with similar splines formed in the piston 11. The stem 23 is also provided with a head 24 carrying pawls 25 which engage the internal teeth 26 of a ratchet ring 27. This ring, pawls and rifle stem constitute the rotation mechanism through which rotation is transmitted to the drill steel 14 in a manner well known in this art.

Under certain conditions of operation, it becomes desirable to release the rotation mechanism, that is, prevent rotation from being transmitted to the drill steel. To that end, there is incorporated in this structure the rotation control mechanism described in detail in the United States Patent No. 2,129,566. Since this mechanism is not a part of the present invention, no further description of it is thought necessary other than pointing out that it includes a slidable clutch element 28 which, when positioned as shown in Figure 1, enables normal operation of the rotation mechanism, and when moved out of that position, enables operation of the stoper drill without rotation of the drill steel 14.

The clutch element 28 is mounted on a bushing 29 in a manner forming therewith an actuating chamber 30 from which leads a relatively small port 31. Opening into the port 31, there is a similarly small port 32 which is capable of communication with the throttle valve main port 22 through a radial port 33. Opening into the port 31 vis-a-vis the port 32, there is a vent or exhaust port 34 which is somewhat larger than the port 31. The exhaust port 34 leads into the tapered bore 35 of a boss 36 extending transversely of the cylinder housing 10, the purpose of which will be explained later.

The feed mechanism generally designated by B, includes a feed tube 37 extending in parallel with the drilling motor A and being rigidly secured to the ends of the latter through lugs 38 and 39 extending laterally from the motor. The upper end of the feed tube 37 is closed by a fluid tight plug 40, while its lower end is provided with a spacer bearing 41 through which slides a tube or piston rod 42. The lower end of this piston rod is preferably pointed as at 43 for posi-

tive engagement with the ground, and its upper end is formed with a piston assembly 44 mounted on a reduced end 45 and held in position by a retainer 46 which is screwed in the end of the piston rod. The piston head 44 includes cup shaped packings 47 mounted for fluid tight engagement with the inner wall of the feed cylinder 37 during outward movement of the piston rod, which movement is effected by motive fluid admitted on the piston head 44 through the plug 40. To that end, the plug 40 is formed with an annular groove 48 from which leads a radial port 49 and central bore 50. Adjacent the annular groove 48, there is welded on the tube 37 a boss 51 adapted to receive the upper end of a small tube 52, which tube extends from the lug 38, alongside the tube 37 and through the lug 39.

The throttle valve 20 is provided with another radial port 53 capable of communication with a port 54 which opens into the lower end of the tube 52 for supplying motive fluid to the feed piston 44 through the tube 52, welded boss 51, annular groove 48, port 49 and central bore 50. Leading from the port 54, there is a vent or exhaust port 55 which opens also into the tapered bore 35 of the boss 36, but is spaced therein from the exhaust port 34 as clearly shown in Figure 2.

Referring now more particularly to the invention clearly shown in Figure 2, the auxiliary handle C includes a stem 56 formed with a tapered shank 57 closely fitted into the tapered bore 35 of the boss 36, and having a threaded end 58 extending therefrom to receive a retaining nut 59 which engages the end wall of the boss 36. For about half of its length, the nut 59 extends beyond the threaded end 58 where it is internally machined to produce a reduced portion 60 and tapered seat 61 within which is fitted the corresponding end 62 of a stem 63, which is thereby rigidly secured to the cylinder 10 in transversal relation therewith. The stem 63 is externally finished to receive a sleeve valve 64 rotatably mounted thereon in fluid tight relation therewith. The angle of rotation of the sleeve 64 is limited to the distance between the ends of a recess 65, which ends are engageable with a pin or stop 66 carried by the stem 63 as clearly shown in Figure 4. The sleeve 64 is normally maintained in the position shown in Figure 4 by a torsion spring 67. The port 34 which opens into the tapered bore 35 is in constant communication with an annular groove 68 formed on the stem 57. From the groove 68, fluid may flow through a radial port 69 and longitudinal port 70 which extends into the stem 63 where it normally ends into the sleeve 64 through a radial port 71. Longitudinally spaced from the radial port 71, there is another radial port 72 which opens into the open end 73 of the stem 63. The two radial ports 71 and 72 may be united by a longitudinal groove 74 provided in the sleeve valve 64.

The stem or handle 56 protrudes from the boss 36 where it is accessible by the operator and is provided with a relatively large flat bottom bore 75 from which leads a smaller central bore or port 76 which is in constant communication with the port 55 through radial ports 71 and an annular groove 78. Seated on the bottom of the bore 75, there is a valve block 79 having a stem 80 and a central bore 81, which bore is in constant communication with the exterior of the stem 56 through radial ports 82, annular groove 83 and vent 84. Slidable within the bore 81, there is a

valve 85 capable of fluid tight engagement with the inner end of the bore for normally closing the bore 76 from the bore 81. The valve is normally held in closed position by a compression spring 86 located in the bore 76. The valve block 79 is held in position by a gland nut 86 screwed into the bore 75 and having a push button 87 slidable therein and on the stem 80 for actuating the valve 85. The push button is normally maintained in its extended or valve closed position by a compression spring 88.

In practice, the drilling apparatus may be held in drilling position by the operator grasping the auxiliary handle C which includes the stem 56, nut 59 and 64, or a handle 89 secured to the front housing 16 of the drilling motor and located above the auxiliary handle C.

In the operation of the tool, motive fluid from the throttle valve 20 is supplied to the automatic valve 18 through ports and passages, not shown, and therefrom to the ends of the cylinder 19 for effecting the reciprocation of the piston 11 and delivering impacts on the shank 13 of the drill steel 14. When the throttle valve 20, sleeve valve 64 and poppet valve 85 are positioned as shown in Figures 1 and 2, the clutch element 28 of the rotation mechanism is maintained in the position shown in Figure 1 by motive fluid admitted into the actuating chamber 30 through the ports 31, 32 and 33. From the throttle valve port 33 motive fluid is also free to flow into the port 34 and auxiliary handle ports 70 and 71 through groove 68 and port 69, but since the radial port 71 is closed by the sleeve valve 64, the motive fluid will simply remain in the auxiliary handle without affecting the position of the clutch member 28. With the clutch element 28 positioned as shown in Figure 1, the rotation mechanism is made to operate normally for transmitting rotation to the drill steel 14. When it is desired to release or stop the rotation of the drill steel 14, the operator holding on the auxiliary handle C, may simply turn and hold the sleeve valve 64 into engagement of the stop pin 66 with the other end of the recess 65, thereby causing the radial ports 71 and 72 to communicate with each other through the valve longitudinal groove 74 and consequently causing free flow of the fluid through the open end 73. In this instance, since the port 34 is larger than the port 32 and has its opening relative to the port 31 located vis-a-vis that of the port 32, the motive fluid from the throttle valve 20 will be free to flow across the port 31, thus causing a suction or partial vacuum in the actuating chamber 30, causing the clutch element to be shifted and maintained in its other position, not shown. In this last position of the clutch element, the rotation mechanism is made to be inoperative, a condition which will last as long as the sleeve valve 64 is positioned to afford communication between the radial ports 71 and 72. When it is desired to again render the rotation mechanism effective, the sleeve valve 64 may be rotated in the position shown in Figure 2.

During normal operation of the tool, the feed mechanism operates by motive fluid admitted from the throttle valve 20 through ports 53 and 54, tube 52, annular groove 48, port 49 and central bore 50, for acting on the piston 44 and the adjacent closed end of the tube 37. Since the pointed end 43 of the piston tube 43 rests on the ground, the motive fluid thus admitted into the feed cylinder will effect upward or feeding motion of the drilling motor at a predetermined

rate of speed. During this normal feeding operation, the motive fluid is also admitted from the port 54 into the auxiliary handle bore 76 through the port 55, groove 78 and radial ports 77. With the valve 85 closed, the pressure fluid admitted into the auxiliary handle bore 76 will simply remain therein without affecting the operation of the feeding mechanism. When it is desired to reduce the speed at which the drilling motor is fed to the work, the operator may open the valve 85 by pressing the push-button 87 inwardly. In this instance, some of the motive fluid from the port 54 will be free to exhaust from the bore 76 through the ports 82, groove 83 and vent 84, thereby reducing the amount of motive fluid supplied to the feeding mechanism and consequently reducing the rate of speed at which the drilling motor is fed to the work. The extent of reduction of feeding speed is controlled by the more or less complete opening of the valve 85. The size of the different ports as well as the size of the valve proper, are calculated to enable collapse of the feeding mechanism upon full opening of the valve 85.

From the foregoing description, it will be understood that the stoper drill is provided with an auxiliary handle C which extends transversely of the drilling motor, with its free ends projecting from the motor in opposite directions, one end being formed by the stem 56 and accommodating the feed control valve or push button 87, while the other end is formed by the stem 63 on which is rotatably mounted the rotation control sleeve valve 64.

I claim:

1. In a rock drill, the combination with a drilling motor having a cylinder and a piston reciprocable therein and capable of rotation, of a rotation mechanism for selectively effecting such rotation including a clutch element slidable into and out of rotation producing position, of a fluid actuated feed mechanism for said drilling motor, means including ports for admitting and exhausting pressure fluid to and from said clutch element for effecting its slidable movement, means including ports admitting operating fluid to said feed mechanism and exhausting fluid therefrom for reducing its feeding speed, a boss extending transversely of the cylinder of said drilling motor, and means carried by said boss and protruding from the ends thereof to form an

auxiliary handle for the rock drill, said handle including in one end thereof a rotatable sleeve valve having a groove formed on its inner surface, spring means for maintaining said valve in one position or another, a plurality of spaced radial ports in said handle adapted to communicate with one another through said groove upon the rotation of said sleeve for controlling exhaust of pressure fluid from said clutch element and a slide valve in the other end of said handle for controlling exhaust of operating fluid from said feed mechanism.

2. In a rock drill, the combination with a drilling motor having a cylinder and a piston reciprocable therein and capable of rotation, of a rotation mechanism for selectively effecting such rotation including a clutch element slidable into and out of rotation producing position, of a fluid actuated feed mechanism for said drilling motor, means including ports for admitting and exhausting pressure fluid to and from said clutch element for effecting its slidable movement, means including ports admitting operating fluid to said feed mechanism and exhausting fluid therefrom for reducing its feeding speed, a handle secured to said cylinder adapted to be grasped by the operator for normally holding the rock drill to the work, an auxiliary handle extending transversely of said cylinder, and means in said last handle including a rotatable sleeve valve having a groove formed on its inner surface, spring means for maintaining said valve in one position or another, a plurality of spaced radial ports in said handle adapted to communicate with one another through said groove upon the rotation of said sleeve for controlling exhaust of pressure fluid from said clutch element and a spring actuated reciprocating valve in one end of said last handle for controlling exhaust of operating fluid from said feed mechanism.
